UNITED STATES PATENT OFFICE.

JOHN R. ELLIOTT, OF CAMDEN, NEW JERSEY.

PIGEON-FEEDER.

No. 865,778.

Specification of Letters Patent.

Patented Sept. 10, 1907.

Application filed January 2, 1907. Serial No. 350,498.

To all whom it may concern:

Be it known that I, JOHN R. ELLIOTT, a citizen of the United States, residing at Camden, county of Camden, State of New Jersey, have invented a new and useful 5 Pigeon-Feeder, of which the following is a specification.

The purpose of my invention is to secure cleanliness and economy in the feeding of pigeons.

A further purpose of my invention is to make the device adjustable for the purpose of determining the amount of feed to be supplied.

A further purpose of my invention is to provide means of ready access for cleaning my device.

A further purpose of my invention is to provide an 15 automatic closure for the feeding aperture.

A further purpose of my invention is to prevent crowding of the pigeons at the feeding point.

A further purpose of my invention is to restrict the times of feeding by means preventing interference of 20 vermin.

A further purpose of my invention is to close the feed openings during a predetermined portion of the day or night.

A further purpose of my invention is to protect the 25 food against waste and uncleanliness.

A further purpose of my invention is to determine the amount of food which shall be available at all times.

My invention further consists of novel details of construction, all as will be hereinafter fully set forth.

30 Figure 1 represents a perspective view of one form of construction embodying my invention. Fig. 2 represents a cross-section of Fig. 1 upon line $x-x$. Fig. 3 represents a side elevation of a closing mechanism. Fig. 4 represents a portion of a closing mechanism embodying 35 a modification of that shown in Fig. 3.

Similar numerals of reference indicate corresponding parts in the figures.

Referring to the drawings: 1 designates a plurality of posts upon which is preferably mounted my structure, 40 the posts being united in the form shown by guards 2 and supporting a top 3 and a table 4. The guards 2 prevent too free access of the pigeons to the feed openings 5 in the plate 6.

Within the frame which I have described, or within 45 any suitable or similar frame, I mount a holder 7, within which the feed 8 is intended to be contained, said holder being mounted in the form shown, by means of a threaded support 9, which performs several functions in that it affords means for support of the holder or container 8, means for adjustment of the height of the same and a filling tube for the insertion of the food within the container. The cap 10 is held against rotation in any suitable manner as by a pin 11 fitting in a slot 12 within the tube 9. It will thus be seen that the tube 50 and container can be raised and lowered readily by turning upon the cap 10. I support the threaded tube

9 within a threaded flange 13, which I have shown as secured against rotation upon the top 3, by means of pins 14. Other means of adjustment could evidently be used.

60 In the side of the container at any suitable point or points, I form a longitudinal opening 15 closed by means of a transparent plate 16, preferably of glass or similar transparent or translucent material, this opening affording means for determining the height of the food in the container without removal of the cap 10.

The container 7 preferably terminates in a tube or mouth piece 17, within which I place any desired form of valve 18 by which the flow of food can be stopped or regulated. The tube 17 preferably extends 70 below the plate 6 into the chamber formed by a drawer 19 having a bottom 20, front 21, rear end 22 and sides 23. The end 22 is most desirably pivoted to swing either way and spring supported in both directions as at 24, so that it may pass the tube 17 in either direction 75 without injuring the end. With this construction the drawer may be removed or replaced with the tube 17 in place. When it is desired to clean the drawer for any purpose, the supply of material is cut off by the valve 18 and the drawer is removed. Any portion 80 of the contents of the drawer which can be used again can readily be returned to the drawer or receiver and the drawer returned to place.

The ring or plate 6 with its openings 5 permits the feeding of but a single bird at each opening. It thus 85 prevents interference with the feeding. At the same time, the supports or standards 1 likewise prevent too much crowding of the birds.

The depression of the feeding floor below the level upon which the bird stands is a most desirable thing, 90 but has been considered inconsistent with suitable accessibility of the feeding floor for cleaning purposes and protection of the food against waste. With my invention the lateral displacement of the food by the birds when feeding is restricted and does not remove 95 the food from the feeding box or floor and it is possible to limit the number of birds feeding at one time and to suitably cover and protect the food against dust and dirt.

In order to protect against mice or like animals, I 100 may provide an automatic closure cutting off communication with the openings 5. I illustrate one form of this automatic closure in Figs. 3, and 4 using slightly different operating mechanism in the two figures.

In Fig. 3 I have shown a motor mechanism embodying a pendulum 26 bearing on an escapement 27, which by means of its latch wheel 28 and the train of pinions and gears 29, 30, 31, 32, 33 and 34 regulates the release of spring 35, which release carries the ratchet wheel 36 about and moves the arm 37. The ratchet 110 wheel is controlled by a latch 38. The movement of the arm 37 is communicated by means of link 39

to a yoke 40 which is connected to a sleeve or cylinder 41 inclosing the feed chamber 7. In its lowermost position the cylinder 41 will evidently close the space through which the poultry or pigeons are intended 5 normally to feed and will thus not only cut off access of the poultry to said space but will prevent access of vermin thereto. The times of movement of the arm 37 may evidently be arranged as desired.

Where a large number of birds are to be fed and 10 where the time during which the feeding apertures should be opened is therefore to be extended or where for any other reason it is desirable to vary the opening and closing of this mechanism so as to open and close it more quickly, or for different lengths of time than 15 would occur with mechanism such as shown in Fig. 3, I provide mechanism of the character shown in Fig. 4 in which a casing or sleeve 42 is lifted by the yoke 43 which yoke is pivoted at 44 and extended in the form of an arm 45, which comes within the path of any suitable cam 46 upon a shaft 47, said shaft 47 corresponding to shaft 48 of my mechanism of Fig. 3 or to any desirable or suitable motor shaft. I have shown this shaft 47 driven by a gear 49 but it might be otherwise driven or even moved by hand. The design of the cam 25 will determine the proportion and relation of opening and closing time and the speed of movement.

It will be evident that various forms of container may be made use of and that other means may be used to adjust the height of the container or of the feed 30 floor 20, so as to vary the distance therebetween.

It will be evident that other means than the drawer 19 may be made use of to secure ready removal of this feeding floor for cleansing purposes.

It will be evident that other automatic closures than

my device shown in Figs. 3 and 4 may be used to some 35 advantage and without departing from my invention, still securing a portion of the benefit thereof.

Having thus described my invention, what I claim as new and desire to secure by Letters Patent, is:—

1. In a device of the character described, a feeding 40 floor, a table above the level of the feeding floor, and a vertically adjustable container opening in proximity to said feeding floor.

2. In a device of the character described, a feeding 45 table, a feeding floor below the level thereof, a container having an opening therein, and means for relatively adjusting the floor and container to vary the distance therebetween.

3. In a device of the character described, a table, a removable floor depressed with relation thereto, a container 50 emptying in proximity to said floor, and means for shutting off the flow from the container.

4. In a device of the character described, a feed chamber having openings permitting access to the feed, a casing movable longitudinally of said chamber, and time 55 actuated mechanism for moving the casing.

5. In a device of the character described, a feeding chamber having an opening permitting access to the feed, means for cutting off access to the feed, a cam actuating said means, and independent means for moving said cam. 60

6. In a device of the character described, a feeding chamber having an opening permitting access to the feed, means for cutting off access to the feed, and time actuated mechanism for moving said closing means.

7. In a device of the character described, a feed chamber, means for mounting said chamber to provide feeding space therebelow, a casing movable longitudinally of said chamber and means for automatically moving the casing along said chamber. 65

JOHN R. ELLIOTT.
